NEEDLE SUPPORT FOR KNITTING MACHINES

Filed Oct. 13, 1932.

FIG. 1. FIG. 1a. FIG. 2. FIG. 3. FIG. 4.

INVENTOR:

ROBERT H. LAWSON

By Roy T. Lovell,
ATTY.

UNITED STATES PATENT OFFICE

2,050,060

NEEDLE SUPPORT FOR KNITTING MACHINES

Robert H. Lawson, Pawtucket, R. I., assignor to
Hemphill Company, Central Falls, R. I., a corporation of Massachusetts

Application October 13, 1932, Serial No. 637,573

8 Claims. (Cl. 66—115)

This invention relates to a knitting machine and more particularly to a construction of needle bed which may be used for guiding jacks as well as needles.

5 In the drawing:

Fig. 1 is a sectional view of a needle bed which may be in the form of a needle cylinder;

Fig. 1a is a view similar to Fig. 1 but showing a modified construction of needle bed;

10 Fig. 2 shows side and end views of one of the needle walls which walls are adapted to be assembled in tricks or grooves provided in the needle bed or cylinder;

Fig. 3 shows views in side and end elevation 15 of a wire or other member which is adapted to be assembled in the needle bed to provide a hardened support for a needle;

Fig. 4 is a view in section similar to Fig. 1 but showing the parts shown in Figs. 2 and 3 assembled with the needle bed;

Fig. 5 is a fragmentary view in front elevation of the elements disclosed in Figs. 2 and 3 in assembled position;

Fig. 6 is a detail view of an element for retaining the needle walls in position in the needle bed; and

Fig. 7 is another view of the retaining means shown in Fig. 6.

The needle bed indicated generally by the numeral 1 consists of two parts 2 and 3 detachably secured together as by means of screws 4. The outer face of the portion 2 of the needle bed is provided with a series of tricks or grooves 5 defined by walls 6. Adjacent to the upper end 35 of the portion 2 there is a recess 7 undercut as at 8, within which recess readily removable walls 9 are insertable. When a wall is inserted as indicated in Fig. 4, a lateral projection 10 seats within the recess 7 the upper edge of which projection 10 is beveled as at 11 to fit the undercut portion 8. The walls 6 are notched or recessed as at 12, hardened wire or other metallic elements 13 being assembled with the needle bed as indicated in Figs. 4 and 5. Such elements are 40 between adjacent walls 9, and serve when in position in the needle bed as shown in Figs. 4 and 5, to provide hardened surfaces to accommodate the sliding movements of the needles and/or jacks. The wires or other elements 13 are offset as at 14, the offset portion of each element 45 consisting of diverging arms so that, in assembling, such offset portions 14 of the elements 13 may be sprung or snapped into the recesses 12, thus being frictionally retained therein. 50 Adjacent to the lower ends of the walls 6 and

slots 5, plates such as 15 are inserted in a recess 16 and retained in position therein as by means of screws 17. As will be noted from inspection of Fig. 4, the plates 15 have their opposite faces beveled so as to wedge into engagement with a wall of the needle bed and the lower faces or edges 18 of the needle walls, such engagement causing the projections 10 of the needle walls to be maintained in firm engagement with the upper portion or face of the needle bed defining the notch or groove 7.

Whereas in Fig. 1 the needle bed or cylinder is shown as consisting of two parts connected by means of a screw 4, in Fig. 1a the needle bed or cylinder 1' is shown as being integral.

The needle beds 1 and 1' may be integral or may be made in sections connected together; furthermore, the needle beds may constitute a so-called flat needle bed or a needle cylinder.

In the foregoing description needles and jacks 20 have been referred to as being adapted to slide in the slots provided in the needle bed. Similarly elements such as 13 may be utilized for supporting sinkers or other knitting instrumentalities which are slidable in sinker heads or like 25 supports.

Whether the knitting instrumentalities are slidable in slots provided in a needle bed having integral or removable walls as shown in the drawing, or are slidable in other supports, the 30 use of hardened elements such as 13 permits the use of a needle bed or other knitting instrumentalities support made of relatively soft material.

I claim:

1. An element adapted to be inserted in a knitting machine and act as a support for knitting instrumentalities, consisting of a wire-like member having a bent portion intermediate its ends by which it is adapted to be removably held in position in a knitting instrumentality bed.

2. An element adapted to be inserted in a knitting machine and act as a support for knitting instrumentalities, consisting of a strip-like element such element being provided with an offset intermediate its ends for frictional and detachable 45 engagement with a needle bed the parts being so constructed that the needle supporting element may be readily inserted in and removed from the knitting machine.

3. A needle bed for a knitting machine provided with needle walls between adjacent ones of which needles or jacks are adapted to slide, a strip-like element offset between its ends, separate from the needle bed, being frictionally held within a slot of the needle bed and between two 55

mentioned walls thereof the parts being so constructed that the strip-like element may be readily inserted in and removed from the needle bed.

4. A needle bed for a knitting machine provided with removable needle walls between adjacent ones of which needles or jacks are adapted to slide, a strip-like element offset between its ends, separate from the needle bed, being frictionally held within a groove of the needle bed and between two mentioned walls thereof the parts being so constructed that the strip-like element may be readily inserted in and removed from between the two mentioned walls.

5. A bed for a knitting machine said bed having slots therein defining walls, elements seated on the outer edges of the said walls and being frictionally and removably retained therein and readily removable therefrom, needle walls removably seated within the mentioned slots and defining, in conjunction with the mentioned elements, raceways for knitting instrumentalities.

6. A needle bed for a knitting machine having needle walls between which needles are adapted to slide longitudinally of the needle bed, a recess extending transversely of the needle bed and strip-like elements offset intermediate their ends, such offsets being received within the recess, the ele-

ments being retained in position in the needle bed by frictional engagement between the offsets and the walls of the recess, the said elements serving to support the knitting instrumentalities in their sliding movements the parts being so constructed that the strip-like elements may be readily inserted in and removed from the needle bed.

7. A wire-like element adapted to be inserted in a knitting machine and act as a support for knitting instrumentalities, said element being offset between its ends to provide diverging arms for frictional engagement in a needle bed of a knitting machine.

8. A needle bed for knitting machines, said needle bed having needle walls between adjacent ones of which needles or jacks are adapted to slide, an element offset between its ends and separate from the needle bed said element being frictionally held within a slot of the needle bed and between two mentioned walls thereof, the parts being so constructed that the said element may be readily inserted in and removed from between the two mentioned walls, such construction of the parts including diverging arms defining the offset.

ROBERT H. LAWSON.
